[57] CLAIM

The ornamental design for a table, as shown and described.

DESCRIPTION

FIG. 1 is a perspective view of my table design;
FIG. 2 is a perspective view of the rear of my design;
FIG. 3 is a top view of my design;
FIG. 4 is an elevational side view of my design;
FIG. 5 is an elevational front view of my design;
FIG. 6 is a sectional view taken along the section lines 6—6 in FIG. 5;
FIG. 7 is an elevational rear view of my design; and
FIG. 8 is a bottom view of my design.
The side of the table not shown is identical to the side shown in FIGS. 1, 2 and 4.
